UNITED STATES PATENT OFFICE

FREDERICK O. SNOW, JR., OF WINCHESTER, MASSACHUSETTS, ASSIGNOR TO MEAD-MORRISON MANUFACTURING COMPANY, OF EAST BOSTON, MASSACHUSETTS, A CORPORATION OF MAINE

EXCAVATOR

Application filed June 25, 1931. Serial No. 546,783.

This invention relates to power excavators, and is concerned with a novel latch-tripping mechanism for the door of the excavating scoop. The invention will best be understood by reference to the following description, when taken in connection with the accompanying drawings of an excavator embodying the invention, while its scope will be pointed out more particularly in the appended claims.

In the drawings:

Fig. 1 is a side elevation of an excavator embodying the invention;

Fig. 2 is an elevation of the scoop with its door and door latch;

Fig. 3 is a sectional view on line 3—3 of Fig. 2;

Fig. 4 is a side elevation of a portion of the latch controlling mechanism and a portion of the mechanism which moves the scoop in and out, and controls such movements of the scoop;

Fig. 5 is a sectional view on line 5—5 of Fig. 4;

Fig. 5A is a plan of a portion of the mechanism shown in Fig. 5;

Fig. 5B is an elevation of the parts shown in Fig. 5A, as viewed from the right-hand side thereof;

Fig. 6 is a sectional view on line 6—6 of Fig. 5;

Fig. 7 is a sectional view on line 7—7 of Fig. 5;

Fig. 8 is a plan of a portion of the latch-controlling mechanism;

Fig. 9 is a side elevation of a portion of the latch-controlling mechanism;

Fig. 10 is an elevation of the parts shown in Fig. 9, as viewed from the left-hand side of Fig. 9;

Fig. 11 is a sectional view on line 11—11 of Fig. 8; and

Fig. 12 is a sectional view on line 12—12 of Fig. 9.

Referring to the drawings, and to the embodiment of the invention which is illustrated therein, there is shown a scoop which may take various forms, the one herein shown by way of example being a dipper 20, rigidly affixed to a dipper stick 21, some-

times called a dipper handle, which is mounted to slide lengthwise in a guide 22, its outward movement being limited by a stop 23 affixed to the dipper stick, and its inward movement by a stop 24 affixed to the dipper stick. The guide 22 is pivoted at 25 on a boom 26, the latter being pivoted at 27 on a swing body 28, which is mounted on a traction base 29. The boom is raised and lowered by a boom rope or cable 30, operated by a boom drum 31, and the dipper stick is raised and lowered by a hoist rope or cable 32, operated by a hoist drum 33.

Inward and outward movements of the dipper stick are produced by a crowd rope 34 or cable 34, and a pull-back rope or cable 35, each having one end anchored to a guard drum 36, said cables being wound in opposite directions thereon. The crowd cable 34 has its other end anchored at 37 on the pivoted guide 22, and leads first rearwardly about a sheave wheel 38 at the rear end of the dipper stick, and then forwardly about a sheave wheel 39, which is coaxial with the pivot 25, thence rearwardly and downwardly part way about a sheave wheel 40, and thence rearwardly and upwardly about the drum 36, to which, as previously stated, the first end of the cable is secured. Thus, it is evident that when the drum 36 is rotated clockwise, as viewed in Fig. 1, the crowd cable 34 is wound in and the resultant pull on the sheave wheel 39 urges the dipper stick 21 outwardly to crowd the dipper 20 into the material to be excavated.

The pull-back cable 35 is anchored at 41 on the boom 26, and leads therefrom first forwardly to and part way about a sheave wheel 42 at the outer end of the dipper stick, thence inwardly and rearwardly to and over a sheave wheel 43 coaxial with the sheave wheel 39, thence downwardly and rearwardly under a sheave wheel 44 coaxial with the sheave wheel 40, and thence upwardly and rearwardly to the upper side of the drum 36, to which as before stated the first end of the pull-back cable is secured. Thus, it is evident that when the drum 36 is rotated contraclockwise, the pull-back cable 35 is wound in and the pull which is

exerted on the sheave wheel 42 at the outer end of the dipper stick pulls the latter inward or backward.

The mechanism for driving the crowd drum 36 and for controlling its operation will now be described, reference being had at first to Fig. 5. A shaft 45 is mounted in bearings 46 and 47 in frame members 48 and 49, respectively, on a base 50 (see Fig. 4). 5 Axial movement of the shaft in one direction is prevented by appropriate means, herein a ball thrust bearing 51, interposed between the journal bearing 47 and a collar 52, suitably secured to the adjacent end of 10 the shaft 45.

The drum 36 is loosely mounted on the shaft 45, but may be driven by the latter through an appropriate clutch, herein comprising two clutch members 53 and 54, one 20 secured to the shaft, as by a key 55, and the other in the present instance being conveniently formed on the drum 36. Herein, power is applied to the shaft through a gear 56, conveniently formed on the clutch member 53. The latter is provided with a facing 25 57 of appropriate material.

Engagement and disengagement of the clutch is effected by sliding the drum and the clutch member carried thereby axially 30 on the shaft. The clutch is normally disengaged by a spring 58 one end of which bears against a hub 59 presented by the clutch member 53, and the other end against a yoke or collar 60, which in turn operates 35 through a ball-thrust bearing 61 against a hub 62 presented by the drum 36. Movement of the yoke or collar under the influence of the spring is limited by suitable means, herein stops comprising nuts 63 40 threaded onto stubs 64 which extend loosely through the clutch member 53, and are fixedly secured to the yoke or collar 60, as by being screwed into the latter. Movement of the clutch member 53 toward the adjacent bearing 46 is prevented by a shoulder 65, presented by the shaft 45.

Engagement of the clutch in opposition to the spring 58 is effected by suitable mechanism, such as that disclosed in Letters Patent 50 No. 1,247,564, issued to Almon E. Norris November 20, 1917, said mechanism comprising a collar 66 mounted on the shaft 45 presenting an abutment 67 for a ball-thrust bearing 68, which is interposed between said 55 abutment and a hub 69 presented by the drum 36. Between said hub and said abutments, there is a body later to be described, by which the thrust of the collar 66 through the thrust bearing 68 is communicated to the drum 36 to slide the latter axially against the yielding opposition presented by the spring 58, thereby to effect engagement of the clutch members 53 and 54.

A yoke 70, encircling the collar 66 and 60 pivoted at 71 thereto, carries a pair of ad-

justing screws 72, presenting abutments 73 for endwise engagement with pins 74 carried by screws 75 threaded into nuts 76 fixedly secured in the frame member 49. Simultaneous rotation of these screws in the proper direction causes an endwise thrust to be exerted against the abutments 73 carried by the yoke 70, thereby moving said yoke and the thrust collar 66 toward the drum 36. The clutch engaging screws 75 are formed 70 on rockshafts 77, which, as shown in Fig. 4, are suitably connected to each other for simultaneous operation by bell-crank levers 78 and 79 secured to said shafts, and having arms 80 and 81 connected to each other by 75 a link or links 82.

Still referring to Fig. 4, a hand lever 83, fulcrumed on a pivot 84, is suitably connected to the bell-crank lever 78, as by a link 85, an arm 86, a rockshaft 87, an arm 88 and a link 89. This hand lever is shown in its neutral position in Fig. 4. Movement of the handle toward the left in Fig. 4,—that is to say, toward the operator who stands facing the lever from that side, operates through the described mechanism to engage the clutch. When the lever is moved back to its neutral position, the clutch releasing spring causes disengagement of the clutch. 90

Referring again to Fig. 5, the shaft 45 is rotated by power in the direction of the arrow thereon,—that is to say, clockwise as viewed in Fig. 4. Accordingly, when the described clutch is engaged, the drum 36 is rotated clockwise by the power of the engine or motor. There is associated with the drum an automatic brake now to be described, which permits free rotation of the drum by power clockwise, but normally prevents rotation counterclockwise. Referring now to Fig. 7, this brake comprises a brake-drum 90, herein conveniently formed as an integral part of the drum 36, which brake-drum operates with a brake member exemplified 100 by a brake-band 91 provided with two relatively movable terminals 92 and 93. These terminals are differentially connected to a hanger, herein a link 94, which is pivoted at 95 to a suitable fixed support, such as a bracket 96, mounted on the base of the machine. The terminal 92 is connected by one or more, herein a pair of links 97 and a pivot 98 to the link 94. The terminal 93 is connected to the link in a manner which 105 will appear presently.

A suitably arranged spring 99 urges the link 94 toward the right (Fig. 7),—that is to say, clockwise about its pivot 95, but in a generally counterclockwise direction considered with reference to the brake-drum. Movement of the link in such direction is limited by an appropriate stop 100, herein conveniently formed as an integral part of the bracket 96. The spring shown is heli- 110 115 120 125 130

cally coiled about a rod 101, which extends freely through an opening 102 provided in the link 94, and thence through the bracket 96 which presents a mounting therefor.

5 One end of the spring rests against a suitable abutment, such as an appropriately curved surface 103 on the link 94, said surface permitting limited rocking movement of the link with relation to the rod. The 10 other end of the spring rests against an abutment, herein a washer 104 and a nut 105, the latter being threaded onto the rod 101.

The relative arrangement of the brake parts thus far described is such that when 15 the brake-drum is rotated clockwise as viewed in Fig. 7, the spring 99 yields and allows the link 94 to swing toward the left, the differential action of the brake-band thereby permitting the latter to relax. When, however, there is any tendency of the brake-drum to rotate contra-clockwise, such tendency is resisted by automatic application of the brake. The brake may be released at 20 will, however, by moving the terminal 93 clockwise, considered with reference to the brake-drum. This is conveniently accomplished by connecting the terminal 93 to the link 94 by a rocking lever 106, having two short arms 107, which are side by side, and 25 embrace said terminal. The link 94 is bifurcated to embrace the rocking lever 106, as well as links 97 (see the upper right-hand portion of Fig. 5).

When the lever 106 is rotated contraclockwise about its fulcrum (Fig. 7), its arms 107 swing toward the left, and the brake-band is relaxed, thereby freeing the brake-drum 90 and allowing it to rotate contraclockwise. It should here be understood that this 30 release of the brake is effected without disturbing the spring 99 and link 94—that is to say, it is accomplished irrespective of the action of the automatic brake-applying means.

45 The brake-releasing lever 106 is manually controlled by mechanism now to be described, reference still being had at first to Fig. 7. The lever 106 is provided with a second arm 108, which is connected by a link 109 to an arm 110, the latter (see Fig. 5A) being connected by a link 111 to an arm 112 secured to a rockshaft 113, to the other end of which there is secured an arm 114, which is connected by a pair of links 115 to 50 an arm 116 secured to a rockshaft 117. Referring again to Fig. 7, the link 109 is arranged generally parallel with a straight line containing the centers of the pivots of the link 94, and the lever 106, and hence 55 does not interfere with the releasing action of the brake.

60 Referring now to Fig. 4, brake-releasing movement of the rockshaft 117 is yieldingly resisted by a spring 118, which is connected 65 to the rockshaft by an arm 119 of a bell-

crank lever 120 secured to the rockshaft, said arm being connected by a pivot 121 to a rod 122, which carries an abutment 123 against which one end of the spring rests, while the other end of the spring is seated against an abutment 124, in which the rod is mounted to slide. The abutment 124 is provided with a pivot 125, which turns in the adjacent frame member 49. When, therefore, the rockshaft 117 is rocked about its axis and the frame 119 swings to and fro, the rod 122 slides forward and backward in the guide 124, and the latter rocks on its pivotal mounting.

70 Release of the brake in opposition to the yielding resistance presented by the spring 99 (see Fig. 7) is effected by the hand lever 83 (see Fig. 4), which operates the clutch, this being accomplished by mechanism now to be described, reference being had to Fig. 4. The bell-crank lever 120 is provided with a second arm 126, connected by a pivot 127 to a sleeve 128, the latter being mounted to slide lengthwise on a rod 129, which is in the nature of a link connecting said arm to an arm 130 on the bell-crank lever 79, which it will be remembered is one of the levers for operating the clutch-engaging screws.

75 Two centering springs 131 and 132 encircling the rod 129, and interposed between the sleeve 128 and abutments 133 and 134 carried by the rod, tend to restore the hand lever and the connected parts to their neutral position. When the arm 130 of the bell-crank lever 79 is turned clockwise by 80 the use of the hand lever 83, it tends to place the spring 132 under compression, and in so doing effects release of the automatic brake, inasmuch as it acts through the sleeve 128, arm 126, rockshaft 117, arm 116 (see Fig. 5A), links 115, arm 114, rockshaft 113, arm 112, link 111, arm 110, link 109 (see Fig. 7) and arm 108, to swing the brake-releasing arms 107 of the lever 106 contraclockwise to release the automatic brake. Since the 85 releasing movement of the brake is through the interposition of the spring 132 (see Fig. 4), the release and reapplication of the brake can be controlled to a nicety, and it can be applied and released gradually and sensitively.

90 The described connections between the hand lever and the automatic brake are such that movement of the hand lever from the neutral position shown in Fig. 4 toward the right (forward from the operator) release the automatic brake. In this connection, it will be remembered that movement of the hand lever to the left (backward toward the operator) engages the clutch. Thus it 95 is apparent that when the operator moves the hand lever backward (toward him), power is applied to rotate the drum 36 clockwise, as viewed in Fig. 4. When the hand lever is restored to its neutral posi-

tion, the clutch is disengaged, and reverse rotation of the drum is prevented by the automatic application of the brake. When, however, the operator moves the hand lever 5 forward (from him), the automatic brake is released, and the drum is free to rotate contraclockwise.

I will now describe the mechanism for urging the drum in the direction opposite to that of the shaft, and at high speed, reference being had to Fig. 5. In the example shown, this mechanism is in the form of a planetary gear set, and comprises an internal gear 135, secured as by a spline 136 to the shaft 45, a sun gear 137 (externally toothed), secured as by pins 138 to the drum 36, and one or more, herein three planet pinions 139, meshing with the gears 135 and 137, and mounted to rotate on studs 140 secured to a planet pinion carrier 141, which is loosely mounted on the hub 69 of the drum 36.

The planet pinion carrier presents a brake-drum 142, cooperating with a brake member, herein a band 143, about the brake-drum. Referring now to Fig. 6, this band has two terminals 144 and 145, one of which is anchored by a pin 146 to a bracket 147, while the other is connected by a pivotal pin 148 to an arm 149 secured as by a key 150 to a rockshaft 151, which is coaxial with and coupled to the rockshaft 117 by a coupling 152.

When the rockshaft 151 is rotated contraclockwise as viewed in Fig. 6, the band is contracted about the drum, and the planet pinion carrier is held against rotation, thus causing the planet pinions to rotate about a fixed axis, and to rotate the sun gear 137 and the drum 36 contraclockwise at high speed. The seating of the brake-applying arm 149 on the rockshaft 151 is such that an extreme forward movement of the hand lever 83 (toward the right in Fig. 4) causes this high speed reverse rotation of the drum 36. Thus when the lever is moved from its neutral position forward (toward the right in Fig. 4), the automatic brake is first released, and further movement of the hand lever in the same direction brings the high speed reverse gearing into operation.

It will be remembered that when the drum 36 is rotated clockwise, it is coupled directly to the driving shaft by the clutch. It follows that the crowding cable, which is urging the dipper into the material, is being wound in at the speed of the driving shaft. It will also be remembered that when the planetary gear set is in operation, the drum 60 is rotated contraclockwise and at high speed. It therefore follows that the pull-back cable is wound in at a correspondingly high speed, and that backward or idle movement of the shovel consequently is speeded up. The control of the forward and backward move-

ments of the dipper stick is vested in the hand lever 83, which therefore controls the in and out movements of the dipper. It is important to remember this, because, as will presently appear, this same hand lever carries the device which controls the tripping of the door latch of the dipper, and hence the operator can trip the door latch at any instant by the same hand which controls the in and out movements of the dipper, and without relinquishing his grasp upon the hand lever.

The dipper, with its door and latch, and the latch-tripping mechanism will now be described, reference being had at first to Figs. 2 and 3. As is usual, one end of the dipper,—that is to say, the digging end, is open, and the other end is provided with a door 153, which is pivoted at 154 at the top of the dipper. This door is normally locked in its closed position by a suitable latch 155, which, as shown, is slidably mounted in a guide 156, the latter being secured to the door. The lower end of the latch is normally received in an opening 157 in a plate 158 secured to the under side of the dipper. The latch is normally held in door-locking position, and is restored to such position by a suitably arranged spring 159, one end of which abuts against the upper end of the latch, and the other against an abutment 160 secured to the door. A rod 161, secured to the upper end of the latch, extends through the spring, and through the abutment 160, to keep the spring in place. In order to enable the door to slam shut, the lower end of the latch is beveled as at 162, and the upper side of the plate 158 near the outer end of the latter is beveled as at 163, thereby to cause the latch to yield upwardly in opposition to the spring, and to snap into its place in the opening 157.

The latch may be lifted in opposition to the spring by a latch-lifting lever 164, pivoted at 165 on the guide 156, and presenting abutments 166 engaging the under side of an overhanging abutment 167, presented by the latch. Downward swinging movement of the lever (and consequently downward sliding movement of the latch) is limited by an adjustable stop screw 168 threaded into the lever, and engaging at its lower end an abutment 169 on the outer face of the door 153.

The latch lever is lifted or tripped by a latch-tripping rope 170, suitably attached to the lever, as by a clevis 171, secured by a pin 172 to a lug 173 presented by the lever. This rope leads upwardly, and, as shown in Fig. 1, over a sheave wheel 174 carried by the outer end of the dipper stick, thence rearwardly between two sheave wheels 175 carried by the boom, thence over two sheave wheels 176 and 177 at the upper portion of the swing body, thence downwardly over

a vertically movable sheave wheel 178, and finally upwardly to the point 179, where it is dead-ended. Referring now to Fig. 4, it will be seen that the vertically movable sheave wheel 178 is disposed in a loop of the latch-tripping rope or cable. There is hung on the sheave wheel 178 a vertically movable traveler 180, whose weight, together with that of the sheave wheel and other associated parts carried by the traveler, normally maintains the rope or cable in a condition in which it will not trip the latch,—that is to say, as the dipper stick moves inwardly, the weight of these parts takes up the slack, as the loop is enlarged by the descent of the take-up device, and on the other hand when the dipper stick is moved outwardly, the take-up device rises.

By holding the take-up device fixed at any point in its vertical movement, outward movement of the dipper stick may be utilized to cause the latch-tripping rope to exert a pull on the latch, and to trip the latter. To this end, the traveler 180 carries an appropriate clamp (see Fig. 12), comprising two clamping members 181 and 182, disposed on opposite sides, respectively, of a fixed vertical rod 183, whose lower end (see Fig. 4) is secured to a bracket 184, and whose upper end is bent horizontally as at 185, and is secured to a bracket 186. Referring again to Fig. 12, the clamping members 181 and 182 are connected to each other at one pair of ends by a pair of links 187, and their other ends by an arm 188, the latter being mounted on a vertically disposed rockshaft 189, by means which, in effect, is a splined connection, two sides of the shaft being slabbed off as at 190, and the arm 188 being correspondingly shaped to fit the cross-sectional shape of the shaft. The clamp is normally relaxed by a spring 191, one end of which bears against a lug 192 presented by the clamping member 182, while the other end rests against an abutment, herein one of a pair of nuts 193, threaded onto a rod 194, which extends loosely through said lug, and is pivoted at 195 to the links 187. The opening movement of the clamp, under the influence of this spring, is adjustably limited by one of a pair of nuts 196, threaded onto the rod 194, and engaging the lug 192.

Clamping action of the clamp in opposition to the spring is caused by rocking the shaft 189 about its vertical axis, thereby swinging the arm 188 contraclockwise, thus to cause the clamp 181 to approach the rod 183. The clamp 182 is provided with a pair of ears 197, disposed above and below the arm 188 and about the rockshaft 189. The clamping member 182 is attached to the traveler 180 as by ears 198. When, therefore, the traveler moves up and down, the clamp moves with it. The rockshaft 189

is mounted in appropriate upper and lower bearings 199 and 200 (see Fig. 4).

As already intimated, the control of the latch preferably is vested in the same hand which controls the hand lever 83 for controlling the in and out movements of the dipper stick. To this end, there is mounted on the lever 83 a latch controlling member, herein a small lever 201 mounted on a pivot 202 on the lever 83, adjacent to the grasping portion of the latter, and suitably connected to the described vertically movable traveler as by a link 203, whose upper end is pivoted at 204 to the lever 201, and whose lower end is pivoted at 205 to one arm 206 of a bell-crank lever 207, whose other arm 208 is connected by a link 209 to an arm 210, the latter being secured to the lower end of the vertical rockshaft 189 below the base or floor plate 50. The pivotal connection 205 between the link 203 and the arm 206 is disposed with its axis substantially coincident with the axis of the pivot 84, on which the lever 83 is fulcrumed, as a result of which rocking movement of the lever 83 has no effect upon the vertically movable traveler. On the other hand, however, at any point in the movement of the lever 83, the operator may, by simply squeezing the small lever 201 toward the large lever 83, cause the traveler to be held in fixed position, as a consequence of which outward movement of the dipper stick under the control of the lever 83 will cause the latch to be tripped. In practice, the operator by forward movement of the lever 83 causes the dipper to be moved outwardly toward the pin where the load is to be discharged, and just a few inches before the dipper reaches that point, the operator presses his thumb or the palm of the hand adjacent the base of the thumb against the lever 201, thus squeezing the latter toward the grasping portion of the lever 83. A slight further movement of the dipper in an outward direction causes the door latch of the dipper to be tripped, and the latch to be discharged.

Having thus described one embodiment of the invention, but without limiting myself thereto, what I claim and desire by Letters Patent to secure is:

1. In an excavator, the combination of a scoop provided with a door, a latch for holding said door closed, a latch-tripping rope, a take-up for said rope, a guide for said take-up, a clamp carried by said take-up, means for moving said scoop, means consequent upon movement of said scoop to cause said rope to trip said latch, and means controlled by the operator to cause said clamp to clamp said guide, thereby to hold said take-up fixed, thereby to predetermine the point in the movement of said scoop when said rope will trip said latch.

2. In an excavator, the combination of a scoop provided with a door, a latch for holding said door closed, a latch-tripping rope, means for moving said scoop, a normally operative take-up device which maintains said rope in a condition in which it will not trip said latch, a guide for said take-up device, a clamp carried by said take-up device, and means at will to cause said clamp to clamp said guide, thereby to render said take-up device inoperative, thereby to cause said rope to trip said latch when said scoop is moved.

3. In an excavator, the combination of a scoop provided with a door, a latch for holding said door closed, a latch-tripping rope, means for moving said scoop, a take-up device which takes up slack in said rope and maintains the same in a neutral condition with respect to said latch, a guide for said take-up, a clamp carried by said take-up, and means at will to cause said clamp to clamp said guide, thereby to render said take-up device inoperative, thereby to cause said latch to be tripped when movement of said scoop subjects said rope to tension.

4. In an excavator, the combination of a scoop provided with a door, a latch for holding said door closed, a latch-tripping rope connected to said latch, a portion of said rope being arranged in the form of a loop, means to move said scoop to and fro, take-up means in said loop automatically responsive to movements of said scoop to take up slack in said rope by varying the size of said loop, a guide for said take-up means, a clamp carried by said take-up means, and means at will to hold said take-up means fixed by causing said clamp to grip said guide.

5. In an excavator, the combination of a scoop provided with a door, a latch for holding said door closed, a latch-tripping rope connected to said latch, a portion of said rope being arranged in the form of a loop, means to move said scoop to and fro, gravity controlled take-up means in said loop automatically responsive to movements of said scoop to take up slack in said rope by varying the size of said loop, a vertical guide for said take-up means, a clamp carried by said take-up means, and means at will to hold said take-up means fixed by causing said clamp to grip said guide.

6. In an excavator, the combination of a scoop provided with a door, a latch for holding said door closed, a latch-tripping rope connected to said latch, a portion of said rope being arranged in the form of a dependent loop, means to move said scoop to and fro, gravity-controlled means including a body supported by said loop and varying the size of the latter as said scoop is moved to and fro, a guide for said body, a clamp carried by said body, and means at will to

hold said body fixed by causing said clamp to grip said guide.

7. In an excavator, the combination of a scoop provided with a door, a latch for holding said door closed, a latch-tripping rope, a take-up for said rope, a guide for said take-up, a clamp carried by said take-up, said clamp comprising two clamping members disposed on opposite sides, respectively, of said guide, means for moving said scoop, means consequent upon movement of said scoop to cause said rope to trip said latch, and means controlled by the operator to move said clamping members toward each other and toward the interposed guide, thereby to hold said take-up fixed, thereby to predetermine the point in the movement of said scoop when said rope will trip said latch.

8. In an excavator, the combination of a scoop provided with a door, a latch for holding said door closed, a latch-tripping rope, a take-up for said rope, a guide for said take-up, a clamp carried by said take-up, said clamp comprising two clamping members disposed on opposite sides, respectively, of said guide, a spring normally relaxing said clamp, means for moving said scoop, means consequent upon movement of said scoop to cause said rope to trip said latch, and means controlled by the operator to move said clamping members toward each other and toward the interposed guide, thereby to hold said take-up fixed, thereby to predetermine the point in the movement of said scoop when said rope will trip said latch.

9. In an excavator, the combination of a scoop provided with a door, a latch for holding said door closed, a latch-tripping rope, a take-up for said rope, a guide for said take-up, a clamp carried by said take-up, said clamp comprising two clamping members disposed on opposite sides, respectively, of said guide, a spring normally relaxing said clamp, means adjustably limiting the relaxing movement of said clamp under the influence of said spring, means for moving said scoop, means consequent upon movement of said scoop to cause said rope to trip said latch, and means controlled by the operator to move said clamping members toward each other and toward the interposed guide, thereby to hold said take-up fixed, thereby to predetermine the point in the movement of said scoop when said rope will trip the latch.

10. In an excavator, the combination of a scoop provided with a door, a latch for holding said door closed, a latch-tripping rope, a take-up for said rope, a guide for said take-up, a clamp carried by said take-up, said clamp comprising two clamping members disposed on opposite sides, respectively, of said guide, an arm carried by said take-up and connecting said clamping members

- to each other, means for moving said scoop, means consequent upon movement of said scoop to cause said rope to trip said latch, and means controlled by the operator to move said clamping members toward each other and toward the interposed guide, thereby to hold said take-up fixed, thereby to predetermine the point in the movement of said scoop when said rope will trip said latch. 5
11. In an excavator, the combination of a scoop provided with a door, a latch for holding said door closed, a latch-tripping rope, a take-up for said rope, a guide for said take-up, a clamp carried by said take-up, said clamp comprising two clamping members disposed on opposite sides, respectively, of said guide, an arm carried by said take-up and connecting said clamping members to each other, a rock-shaft extending lengthwise of said guide and having a splined connection with said arm, means for moving said scoop, means consequent upon movement of said scoop to cause said rope to trip said latch, and means controlled by the operator to move said clamping members toward each other and toward the interposed guide, thereby to hold said take-up fixed, thereby to predetermine the point in the movement of said scoop when said rope will trip said latch. 10
12. In an excavator, the combination of a scoop provided with a door, a latch for holding said door closed, a latch-tripping rope, a take-up for said rope, a guide for said take-up, a clamp carried by said take-up, said clamp comprising two clamping members disposed on opposite sides, respectively, of said guide, a rock-shaft extending lengthwise of said guide, a rocker-arm carried by said take-up and slidable lengthwise of and on said rock-shaft, said rocker-arm having a non-rotatable connection with said rock-shaft and connected to said clamping members to urge them toward said guide, means for moving said scoop, means consequent upon movement of said scoop to cause said rope to trip said latch, and means controlled by the operator to move said clamping members toward each other and toward the interposed guide, thereby to hold said take-up fixed, thereby to predetermine the point in the movement of said scoop when said rope will trip said latch. 15
13. In an excavator, the combination of a scoop provided with a door, a latch for holding said door closed, a latch-tripping rope, a take-up for said rope, a guide for said take-up, a clamp carried by said take-up, said clamp comprising two clamping members disposed on opposite sides, respectively, of said guide, a link connecting said clamping members together at one pair of ends, an arm connecting said clamping members together at their other pair of ends, means to rock said arm to cause said clamping members to move one toward the other, a spring normally tending to move said clamping members apart, means for moving said scoop, means consequent upon movement of said scoop to cause said rope to trip said latch, and means controlled by the operator to move said clamping members toward each other and toward the interposed guide, thereby to hold said take-up fixed, thereby to predetermine the point in the movement of said scoop when said rope will trip said latch. 20
14. In an excavator, the combination of a scoop provided with a door, a latch for holding said door closed, a latch-tripping rope, a take-up for said rope, a guide for said take-up, a clamp carried by said take-up, said clamp comprising two clamping members disposed on opposite sides, respectively, of said guide, a link connecting said clamping members together at one pair of ends, an arm connecting said clamping members together at their other pair of ends, means to rock said arm to cause said clamping members to move one toward the other, a spring normally tending to move said clamping members apart, means for moving said scoop, means consequent upon movement of said scoop to cause said rope to trip said latch, and means controlled by the operator to move said clamping members toward each other and toward the interposed guide, thereby to hold said take-up fixed, thereby to predetermine the point in the movement of said scoop when said rope will trip said latch. 25
15. In an excavator, the combination of a scoop provided with a door, a latch for holding said door closed, a latch-tripping rope, a take-up for said rope, a guide for said take-up, a clamp carried by said take-up, said clamp comprising two clamping members disposed on opposite sides, respectively, of said guide, a link connecting said clamping members together at one pair of ends, an arm connecting said clamping members together at their other pair of ends, means to rock said arm to cause said clamping members to move one toward the other, a spring connected to said link and normally tending to move said clamping members apart, means for moving said scoop, means consequent upon movement of said scoop to cause said rope to trip said latch, and means controlled by the operator to move said clamping members toward each other and toward the interposed guide, thereby to hold said take-up fixed, thereby to predetermine the point in the movement of said scoop when said rope will trip said latch. 30
16. In an excavator, the combination of a scoop provided with a door, a latch for holding said door closed, a latch-tripping rope, a take-up for said rope, a guide for said take-up, a clamp carried by said take-up, said clamp comprising two clamping mem- 35

bers disposed on opposite sides, respectively, of said guide, a rock-shaft extending lengthwise of said guide and extending through one of said clamping members, a rocker-arm 5 through which said rock-shaft extends, said rocker-arms connecting said clamping members together at one pair of ends, means connecting said clamping members together at their other pair of ends, means for moving 10 said scoop, means consequent upon movement of said scoop to cause said rope to trip said latch, and means controlled by the operator to move said clamping members toward each other and toward the interposed guide, 15 thereby to hold said take-up fixed, thereby to predetermine the point in the movement of said scoop when said rope will trip said latch.

17. In an excavator, the combination of a 20 scoop provided with a door, a latch for holding said door closed, a latch-tripping rope, a take-up for said rope, a guide for said take-up, a clamp carried by said take-up, said clamp comprising two clamping members 25 disposed on opposite sides, respectively, of said guide, a rock-shaft extending lengthwise of said guide and extending through one of said clamping members, a rocker-arm through which said rock-shaft 30 extends, said rocker-arm connecting said clamping members together at one pair of ends, a link connecting said clamping members together at the other pair of ends, means for moving said scoop, means consequent 35 upon movement of said scoop to cause said rope to trip said latch, and means controlled by the operator to move said clamping members toward each other and toward the interposed guide, thereby to hold said take-up 40 fixed, thereby to predetermine the point in the movement of said scoop when said rope will trip said latch.

In testimony whereof, I have signed my name to this specification.

45 FREDERICK O. SNOW, JR.
